UNITED STATES PATENT OFFICE.

LEE G. DANIELS, OF ROCKFORD, ILLINOIS.

WATER-SOFTENER VALVE MECHANISM.

Application filed May 5, 1927. Serial No. 188,984.

This invention relates to base-exchange water softeners and is devoted more particularly to improvements in the valve mechanism for hand operated softeners, such as are more extensively provided for domestic use.

One of the principal objects is to provide a valve mechanism of an extremely simple and inexpensive type and one which enables the average mechanically unskilled person to put the softener through its regenerations without fear of confusion or mistake and with no need for the use of an instruction book, once the simple method of operation has been committed to a matter of routine.

According to the invention, a valve mechanism is provided operable by a single hand lever shiftable to either one of two limit positions one for softening operation and the other for draining, salt charging and "soaking," there being an intermediate position of the lever in the movement thereof from the draining position to the softening position for the regeneration flow or salt wash. In other words, the operation is reduced to a 1-2-3 routine.

I also prefer to use a simpler method of regenerating the softener, according to which the softener is charged with salt or brine at the end of the capacity run and instead of the salt being washed through the bed of softening material, as is otherwise done, it is permitted to "soak," that is, the brine by reason of its greater density, settles through the bed of softening material to the bottom thereof. The intimate contact with the material necessarily produces efficient regeneration. Then, after the soaking the regeneration flow is commenced, that is, the excess brine and the liberated lime and magnesium hardness from the softening material is flushed out. In connection with this method of operation I have provided a siphon through which the level of the water in the tank is lowered just before the salt or brine is introduced, the siphon having its high point above the level of the filler opening so that once the siphon action is broken or interrupted it is not reestablished during the soaking period which follows the salt charging.

The invention embraces still other novel features and advantages which will be referred to in the course of the following description in which reference is made to the accompanying drawings wherein—

Fig. 1 is a side view of a water softener equipped with my improved valve mechanism

and also having the siphon thereon which permits operating the softener according to my novel method;

Fig. 2 is a front view of the valve mechanism, the same being shown with the hand lever in the #2 position for the regeneration flow or salt wash, while the dotted line position of the lever at the right indicates the #1 position for the draining, salt charging and soaking, and the dotted line position of the lever shown at the left indicates the #3 position for normal softening operation; and

Fig. 3 is a side view of Fig. 2 with one of the valves and its operating pulley appearing in section.

The softener comprises a tank 10 serving as a container for a bed of zeolite mineral, or other water softening material. Hard water is supplied to the softener from any suitable source as, for example, the city water mains, through a pipe 11 and soft water is arranged to be withdrawn to the service system through a pipe 12. A pipe 13 connects at 14 with the lower end of the tank through a distributor pipe 15 or other means for distributing the water flow uniformly throughout the cross-sectional area of the bed of water softening material 16. The dotted line indicates approximately the level to which the tank is filled with the softening material. The head space left at 17 is sufficient to insure the settling out of any material which might tend to rise with the water passing through the tank. A pipe 18 connects at 19, with the upper end of the tank. The valve mechanism, here generally indicated by the reference numeral 20, is arranged to control the connections for the tank 10 with the water supply pipe 11 and with a drain outlet pipe 21, for the three phases of operation of the softener, namely the salt charging operation with its accompanying draining and soaking, the regenerating operation, and the normal softening operation. In the normal softening operation the hard water supplied through the pipe 11 flows through the valve 22 downwardly through the pipe 13, as indicated by the full line arrow, for passage into the lower end of the tank beneath the bed of softening material. The distributor pipe 15, as previously mentioned, distributes the water evenly throughout the cross-sectional area of the bed for uniform contact with the material, and the water in passing upwardly through the bed is softened and supplied to the service system through the pipe 12. At the end

of the capacity run when the softener has to be regenerated the valve mechanism 20 is operated to close the valve 22 so as to shut off communication between the supply pipe 11 and the softener tank. The companion valve 23, on the other hand, is opened to establish communication between the upper end of the tank and the drain pipe 21. The softener is then in readiness for the introduction of the salt or brine through the filler neck 24. The latter has a cap 25 suitably clamped in place by the hand screw device 26 so as normally to seal the tank. When the cap 25 is removed the air seal is, of course, broken and a certain amount of water is siphoned out of the upper end of the tank down to the level of the lower end of the pipe 19. The amount to which the pipe projects down into the tank is indicated clearly in dotted lines. When the level has dropped to this point the siphon action is broken and, of course, there is no further drainage. Furthermore, the siphon action is not reestablished simply by the pouring in of the salt or brine inasmuch as the pipe 27, which represents the high point of the siphon, is above the level of the filler opening. Thus, after the salt or brine is introduced the cap 25 is replaced and the softener may be allowed to stand untouched for a period of soaking during which period the brine, by reason of its greater density, settles through the bed of softening material to the bottom thereof, thus coming into intimate contact with all of the mineral for a complete chemical exchange between the brine and the mineral known as "base-exchange". The soaking is allowed to go on for thirty minutes or more and after that the valve mechanism 20 is operated to partly open the valve 22 and partly close the valve 23. This commences the regeneration flow or salt wash in which the incoming water passes through the valve 22 necessarily at a more or less restricted rate due to the valve being only partly open, and flows downwardly through the pipe 13, as indicated by the dotted line arrow. The water is thus introduced into the bottom of the tank through the distributor pipe 15 which uniformly distributes it throughout the cross-sectional area of the bed for passage upwardly therethrough. In passing upwardly the water picks up the excess brine and the liberated magnesium and lime from the softening material and carries it out through the pipe 19 for discharge to the sewer by way of the drain pipe 21. During this flow if there is any softening material which has not become regenerated during the soaking when the brine settled down through the material, such material is more or less insured of regeneration when the brine is carried upwardly through the material for a second passage therethrough. The increase in efficiency resulting from the carrying of the brine twice through the material will be self-

evident and it will, furthermore, be clear that less salt or brine may be used because of this new method of operation than would otherwise be the case. The regeneration or salt wash is continued only until it is definitely insured that all of the brine has been disposed of. This may be determined by withdrawing and testing samples of the water issuing from the upper end of the tank. A test faucet 28 (see Fig. 2) is preferably provided at the drain pipe 21 for this purpose. It is believed that the novel method of operation of the softener is sufficiently clear from the foregoing description that the special features and advantages of the improved valve mechanism will be readily appreciated when the construction thereof is described.

Referring now more particularly to Figs. 2 and 3 it will be observed that the valves 22 and 23 are ordinary standard globe type valves, the stems 30 and 31 of which are threaded, as indicated at 32, to screw in and out in the closing and opening of the valves. The stems 30 and 31 have small pulleys 33 and 34, respectively, fixed thereto as by means of set screws for the turning thereof. A single hand lever 35 is preferably formed integral with one of the pulleys, in this case the pulley 34, and is arranged to be shifted to the three positions indicated in Fig. 2. The turning of the pulley 34 produces the same turning of the pulley 33 but in the reverse direction by means of a criss-crossed belt connection shown at 36. The latter consists of a flexible wire cable of one continuous length wound in several turns about each of the two pulleys and criss-crossed therebetween in the manner shown, the one end of the cable being knotted, as at 37, where it is passed through an opening 38 provided in the flange of the pulley 34, and the other end being passed through another opening 39 in the pulley 34 and clamped by a screw 40. The cable at about the midpoint thereof is looped through openings 41 in the flange of the pulley 33. In this way the two pulleys have a positive operating connection. The preceding description of the three phases of operation of the softener, that is, for softening, salt charging and soaking, and regeneration, has no doubt made it clear that when the valve 22 is fully opened for softening operation the valve 23 is closed. Then, in the salt charging and draining operation, the valve 22 is closed entirely and the valve 23 is opened entirely. Following that, in the regeneration, the valve 23 which was fully opened is partly closed, and the valve 22 which was fully closed is partly opened. In other words, the reversing operating connection between the two valves causes the one to be opened when the other is closed and vice versa. The fact that the one valve is closed in the opening of the other and vice versa enables an adjustment in the extent to which the valves may be opened. For example, in a

valve which requires two full turns for operating the same from a fully closed to a fully opened position the extent of opening may be adjusted so that the valve will open to the extent of one turn, a turn and a quarter, (which happens to be the setting in the present case), a turn and a half, or as much as two turns, depending on the available water pressure. In a community where the available water pressure is low the valves may be set to open wider than in a case where the available water pressure is high, the thought being to moderate the flow for proper softening of the water and to prevent the carrying off of the mineral in the water by reason of a too heavy flow. In the setting of the valves the amount of valve opening is determined simply by closing the one valve with its pulley clamped thereto and opening the other valve to whatever its fullest extent of opening is to be, and thereupon clamping its pulley to the stem thereof. In other words, the expression "fully opened" as here used is a purely relative one as the extent of opening is variable. It will be evident from the foregoing that with the lever 35 in the dotted position indicated to the left in Fig. 2, corresponding to the #3 position for softening, the lever 35 has to be turned in a counter-clockwise direction approximately a turn and a quarter to the dotted line position indicated at the right in Fig. 2 in order fully to open the valve 23 and fully close the valve 22. There is no need for any indication of a limit position since the operator merely turns the lever in a counter-clockwise direction until it can be moved no farther. Following this, after the salt charging and the soaking, the operator turns the lever in a clockwise direction to the mid position, indicated in full lines in Fig. 2. The operator will use the pipe 18 as a guide in determining fairly accurately the mid position. After the salt wash, the operator moves the lever again in a clockwise direction as far as it will go, which is to the softening position indicated in dotted lines at the left in Fig. 2. It is, therefore, evident that the operation is reduced to a 1-2-3 routine and once the operator has committed this simple system to memory there is no need for consulting an instruction book. If desired, I may provide an index plate 42 fixed either to the body of the valve 23, as at 43, or else to the pipe 18, having the arrows 44 and 45 thereon indicating that the lever should be turned in a clockwise direction to bring it to the softening position and that it should be turned in a counter-clockwise direction to bring it to the salt charging position. The two arrows are, therefore, accompanied with the legends "soft" and "salt". Or, if desired, the two arrows may be provided on the pulley 34 along with the legends to indicate which way the lever 35 should be turned.

I have found it to be a particularly convenient feature to employ a drop T fitting 46 in the connection between the water supply pipe 11 and the valve 22, and a similar fitting 47 in the connection between the drain pipe 21 and the valve 23. This enables dispensing with a union in the pipe between the top or bottom of the tank and the valve mechanism, which is always necessary otherwise, so that an important item of expense is eliminated, and also permits connecting up the softener from either side or from both sides, so far as the valve mechanism is concerned. When the pipes 11 and 21 are brought in at the left hand side the plug 48 and the test faucet 28 will serve to close the T fittings on the right hand side thereof. Drop fittings are equipped with fastening lugs, as indicated at 49, which in the ordinary use of these fittings receive screws or bolts to fasten the same to walls or ceilings along which the pipes threaded therein are extended. In the present case, however, the lower portion and the upper portion of the pipe connections are completed separately and without any unions and are then arranged to be swung together into line 90 for connection by the drop fittings. The latter are disposed back to back and the lugs 49 of the two fittings are arranged in register so that bolts 50 may be entered therethrough to fasten the two parts together. There is, therefore, a considerable saving in the cost of the valve unit and also in the cost of installation.

It is believed the foregoing description conveys a clear understanding of my invention and all of its objects and advantages. It should be apparent that the invention is capable of a certain amount of modification from the particular embodiment herein shown and described and for that reason the appended claims have been drawn with a view to covering all legitimate modifications, adaptations and variations of the invention which may suggest themselves to one skilled in the art as a result of this disclosure.

I claim:

1. In a water softener, the combination with a water softener tank containing softening material, and means for supplying hard water to said tank and withdrawing soft water therefrom, of a pair of valves, one of which controls communication between one end of the tank and the water supply and the other of which controls communication between the other end of the tank and a drain outlet, the stems of both of said valves screwing in the same direction for opening and in the same direction for closing, means for turning one of said valves for opening and closing the same, and a reversing operating connection between said valves whereby in the closing of one the other is opened and vice versa.
2. In a water softener, the combination

with a water softener tank, of a pair of valves, one of which controls communication between one end of the tank and the water supply and the other of which controls communication between the other end of the tank and a drain outlet, the valves being substantially the same and the stems of both valves turning in one direction for opening and in the opposite direction for closing, means for turning one of said valves for opening and closing the same, and a direct, mechanical reversing operating connection between the stems of said valves whereby in the turning of one stem for the closing of one valve the other is simultaneously opened and vice versa.

3. A water softener valve mechanism as set forth in claim 2 wherein the reversing operating connection between the valves comprises pulleys mounted on the stems of the valves, and a belt element wound about said pulleys and criss-crossed between the same.

4. A water softener valve mechanism as set forth in claim 2 wherein the reversing operating connection between the valves comprises pulleys mounted on the stems of the valves, and a belt element wound about said pulleys and criss-crossed between the same, one of the said pulleys being adjustably mounted on said valve stem whereby to permit varying the extent of valve opening movement.

5. A water softener valve mechanism as set forth in claim 2 wherein the operating connection between said valves comprises pulleys fixed on the stems of said valves, and a flexible cable element wound about the pulleys and criss-crossed between the same, the cable being fixed at one point to the periphery of each of the pulleys whereby to provide a positive operating connection between the pulleys.

6. A water softener valve mechanism as set forth in claim 1 wherein the operating connection between said valves comprises pulleys fixed on the stems of said valves, and a flexible cable element wound about the pulleys and criss-crossed between the same, the cable being fixed at one point to the periphery of each of the pulleys whereby to provide a positive operating connection between the pulleys, there being more than one lap of the cable on each of the pulleys to permit more than one complete turn of said valves.

7. A water softener valve mechanism as set forth in claim 2 wherein the one valve is fully closed when the other valve is fully opened and vice versa, the operating connection between said valves being in a one to one ratio, whereby the one valve is arranged to close toward a mid-open position and the other valve is arranged to open toward a mid-open position for the regeneration flow.

8. In a water softener, the combination with a water softener tank, of a pair of valves, one of which controls the inlet of hard water to the tank and the other of which con-

trols the outlet to a drain, and means connecting said valves to operate together, so that as one opens the other closes and vice versa, said means comprising pulleys mounted on the stems of the valves, and a belt element wound about said pulleys.

9. A water softener valve mechanism as set forth in claim 8 wherein one of the said pulleys is adjustably mounted on the valve stem whereby to permit varying the extent of valve opening movement.

10. A water softener valve mechanism as set forth in claim 8 wherein the cable is fixed at one point to the periphery of each of the pulleys whereby to provide a positive operating connection between the pulleys.

11. In a water softener, the combination with a water softener tank having a top filler opening which is normally sealed, of a valve controlling the inlet of hard water to the lower end of said tank, and another valve controlling the outlet to a drain from the upper end of said tank, the connection between the last mentioned valve and the upper end of said tank being such as to cause a predetermined amount of water to be siphoned out of the tank through the valve when said valve is open and the other valve is closed and the tank is unsealed whereby to lower the level of water in the tank to a predetermined distance below the filler opening.

12. A water softener structure as set forth in claim 11 wherein the siphon connection has the high point thereof above the level of the filler opening for the purpose described.

13. In a water softener, the combination with a tank having a top filler opening which is normally sealed, of valve means controlling the inlet of hard water to the lower end of the tank and for controlling the outlet to a drain from the upper end of the tank, and means for siphoning the water out of the tank to a predetermined level when the inlet is closed and the outlet is opened and the tank is unsealed whereby to lower the level of water in the tank to a predetermined distance below the filler opening.

14. In a water softener, the combination with a softener tank containing softening material, and means for supplying hard water to said tank and withdrawing soft water therefrom, of a valve controlling communication between the water supply and one end of said tank, another valve for controlling communication between the other end of said tank and a drain outlet pipe, and a pair of fittings between said valves one for connecting the first valve with the water supply pipe and the other for connecting the other valve with the drain pipe, said fittings being arranged to permit connection with the water supply and drain pipes from either or both sides of said valves, said fittings being of the drop type with fastening lugs projecting in opposite directions from the back there-

of, the fittings being arranged back to back, and having bolts passing through said lugs for fastening the same together.

15. A water softener valve mechanism as set forth in claim 14 wherein the fittings are of the drop **T** type permitting the connection of the water supply and drain pipes therewith from either side in relation to the valves, the other side being arranged to receive a closure such as a test faucet or plug.

16. A water softener, comprising in combination with a tank and valve means for controlling the inlet of hard water to the tank and regeneration of the softening material,

15 pipes connected to the upper and lower ends of the tank and extending toward each other, and drop fittings fastened on the inner ends of said pipes and having the lugs thereof arranged to be fastened together, whereby the

20 lower pipe and the upper pipe may be fastened to the tank ends separately and without unions therein and swung together into line and connected together by means of the lugs of said fitting.

25 17. In a water softener, the combination with a water softener tank, of a pair of valves,

one of which controls communication for one end of the tank and a certain pipe and the other of which controls communication for the other end of the tank and another pipe, 30 the valves being substantially the same and the stems thereof moving in one direction for opening and in the opposite direction for closing, means for operating one of said valves for opening and closing the same, and a direct, mechanical, reversing operating connection between the stems of said valves whereby in the operation of one stem for the closing of one valve the other is simultaneously opened and vice versa. 35

18. A water softener valve mechanism as set forth in claim 8 wherein the cable is fixed at one point to the periphery of each of the pulleys whereby to provide a positive operating connection between the pulleys and 40 wherein there is more than one lap of the cable on each of the pulleys to permit more than one complete turn of said valves. 45

In witness of the foregoing I affix my signature.

LEE G. DANIELS.
